UNITED STATES PATENT OFFICE.

WILLIAM H. AVERILL, OF BOSTON, MASSACHUSETTS, ASSIGNOR OF ONE-HALF TO
ARTHUR C. ERISMAN, OF BROOKLINE, MASSACHUSETTS.

FOUNTAIN PEN.

Application filed May 18, 1921. Serial No. 470,528.

To all whom it may concern:

Be it known that I, WILLIAM H. AVERILL, a citizen of the United States, residing at Boston, in the county of Suffolk and State 5 of Massachusetts, have invented new and useful Improvements in Fountain Pens, of which the following is a specification.

The present invention relates to fountain pens and particularly to the means for filling and refilling such pens with ink.

The object of the invention is, primarily, to enable the pen to be filled without either dipping the pen into ink or pouring ink into the barrel of the pen; and this object is accomplished by providing for the use of such pens a cartridge having stiff walls and adapted to be sold to users already filled with ink and to be placed by the user in a pen and removed when empty to make room 20 for a new filled cartridge.

Another object of the invention is to enable a close, non-leaking, packed joint to be made between the cartridge and the stock of the pen without need of especial care on 25 the part of the user and without fail upon each charging of the pen. This further object is accomplished by the use of a special stopper for the cartridge and a special construction of the pen stock which punctures 30 the stopper, the stopper being further so made as to form a yielding packing between the end of the cartridge and the pen stock.

For a complete illustration and explanation of the preferred manner in which I 35 have carried my invention into practice, attention is directed to the drawings furnished herewith in which there are illustrated three of the possible forms in which the essential characteristics of the invention may 40 be embodied.

In the drawings,—

Figure 1 is a longitudinal sectional view on an enlarged scale of a pen embodying my invention.

Figure 2 is a view of the open end of the cartridge and a stopper for the same having the form and construction shown in Figure 1.

Like reference characters indicate the 50 same parts in all of the figures wherever they occur.

In Figure 1 the barrel is shown as made of two parts *a* and *b* which are detachably secured together by a threaded joint *c* about 55 midway of the barrel. *d* is the stock which

carries the metal pen *e* and the leader *f* for ink by which ink is conducted to the pen point, such stock having a threaded end *d'* which is detachably screwed into the end of the barrel. *g* is the cap which is placed 60 over the pen stock and pen and may be screwed on the barrel by complementary threaded parts *g'* and *a'* in the cap and on the exterior of the barrel, respectively.

As thus far described the pen does not 65 differ from other fountain pens now known and used except in so far as the construction of the pen barrel in two parts is a departure from common construction; but this two part construction is not an essential of 70 the invention, for all essentials thereof may be combined with a fountain pen having a one piece barrel. It is to be understood, also, that any material suitable for fountain pen construction may be employed in 75 making the pen as thus far described.

Within the barrel is a cartridge *h* containing ink, being closed at the end *h'* which enters the closed end of the barrel, and being open at the other end but having 80 a stopper *k* therein. The cartridge may be made of any material which is sufficiently stiff to enable it to be handled without collapsing, to be inserted endwise into an open fountain pen barrel and to sustain the pres. 85 sure applied as hereinafter described by the pen stock in puncturing its stopper. Materials suitable for the purpose are glass, metal, hard rubber, waterproof fiber or paper, and compositions of various sorts. In trans- 90 verse dimensions and outline the cartridge is preferably made to conform as closely as possible with the inside of the barrel and in length to extend from the closed end of the barrel to the pen stock, but being preferably 95 enough shorter than this distance to admit a cushioning piece *l* between the head of the barrel and the closed end of the cartridge.

The stopper *k* has certain characteristics to which attention is called. It is formed 100 with a flange *k'* which overlaps the edge of the cartridge at its open end to form a packing between such end and the base of the pen stock *d* and it also has a transverse wall or web *k''* which extends across and closes 105 the entrance to the cartridge. This web is preferably thin and easily punctured so that it may be broken by the piercing point on the pen stock. Hence in order to permit this wall to be thin enough, and also to give 110

the stopper sufficient bearing on the walls of the cartridge to hold it firmly seated, the stopper is made as a plug which enters to a substantial distance into the bore of the 5 cartridge making contact with the inner surface thereof, but it is also recessed from one end or the other, or permissibly from both ends, whereby the thickness of the web is reduced to a small fraction of the axial 10 length of the entire stopper.

In the pen stock is mounted a piercing point *m* which projects oppositely to the pen point and is of such dimensions that it will enter the open mouth of the cartridge 15 within the walls of the plug; and it is pointed and sufficiently stiff to be capable of puncturing and passing through the end wall *k*² of the stopper. In the side of this piercer is a channel *n* which extends from 20 near the point to its base and opens into the passage *o* through which ink is conducted to the pen point.

A filled cartridge closed by a stopper like the stopper *k* may be placed in the barrel of the fountain pen when either the barrel is taken apart at the joint *c* or the pen stock is removed. Then when the parts of the barrel are brought together, or when the pen stock is replaced, the approach of 25 the barrel head to the stock causes the piercer to enter the cartridge and pass through the end wall of the stopper, thus establishing a channel from the interior of the cartridge to the pen point through 30 which ink may flow. When the stock is screwed tightly into the barrel and the parts of the barrel are screwed tightly together, the cushioning plug *l* and the lip *k*¹ of the stopper are put under compression and 35 the stopper lip is then caused to act as an elastic gasket between the stock of the pen and the end of the cartridge, packing the joint between those parts and preventing leakage of ink.

40 It will be readily understood from the foregoing description that when the ink supply of a pen made according to my invention is exhausted, the supply may be renewed by removing the empty cartridge 45 and substituting a filled one. The substi-

tuted cartridge is sealed and is dry and clean externally, while the packed joint between the exhausted cartridge and the stock of the pen has prevented ink from creeping over the outer surface of the latter. 55 Thus the cartridge may be exchanged without soiling the fingers; and of course the use of such cartridge makes it unnecessary to pour ink into the pen with a filler or to dip the pen point into an ink bottle while 60 manipulating the filling appliances with which some pens are equipped.

The cartridge may be filled with freshly made ink thoroughly filtered and free from dirt or sediment. Being sealed until the 65 time of use, the ink in the cartridge remains in this clean condition and avoids liability of the pen becoming clogged with sediment which exists when the supply is taken from an ink bottle.

70 What I claim and desire to secure by Letters Patent is:

1. A fountain pen comprising a barrel having a head at one end, a pen stock at the other end having an inwardly projecting piercing point provided with an ink conducting channel, and an ink cartridge adapted to enter the barrel and having one closed end and one open end, a stopper penetrable by said piercing point located in 75 the open end of said cartridge and formed with a lip of resilient material overlapping the walls of the cartridge and adapted to be pressed against the adjacent end of the pen stock; and a cushioning piece mounted 80 in the barrel in position to engage the closed end of said cartridge and press the other end against the pen stock.

2. A fountain pen as set forth in claim 1 and in which the stopper for the cartridge 85 is a plug of rubber composition fitting within the open end of the cartridge and having a bead which overlies the edge of the latter, said stopper having a transverse closing wall which is adapted to be penetrated by said piercing point.

90 In testimony whereof I have affixed my signature.

WILLIAM H. AVERILL.
